UNITED STATES PATENT OFFICE.

JOHN THOMAS PILKINGTON, OF VANCOUVER, BRITISH COLUMBIA, CANADA.

CLOTHESLINE-SUPPORTING MEANS.

Application filed January 22, 1926. Serial No. 83,099.

This relation relates to clothesline supports and has particular reference to an improvement in a supporting means for what are commonly termed "endless pulley clotheslines."

One of the principal objects of the present invention is to provide an improved support for endless pulley clotheslines which admits of the full use of the entire clothesline for the support of clothes.

More specifically, the present invention comprehends supporting means for endless clotheslines which includes a plurality of pulleys disposed in substantially horizontal position on a substantially vertical axis from an overhead support, whereby the leads of the line are in approximately the same horizontal plane.

The invention furthermore comprehends a means for tensioning the line so as to preclude the displacement of the line from the pulley, which means, by way of illustration, consists in mounting the pulley-supporting means for tilting or inclining with respect to the horizontal, and providing roller elements engaging the leads of the line.

The invention furthermore comprehends a supporting means of the character set forth which is comparatively simple in its construction and mode of operation, inexpensive to manufacture and install, and which is highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a perspective view illustrating one of the line-supporting and guiding elements associated with the line;

Fig. 2 is a plan view of the same detached from the mounting and with the line removed;

Fig. 3 is a sectional view taken approximately on the line 3—3 of Fig. 2.

Referring to the drawings by characters of reference, A designates a vertical wall or other support; B, a portion of an endless clothesline.

The supporting means constituting the present invention, (a plurality of which it is

of course understood, are employed for supporting the line), consists of a grooved pulley 10 mounted for rotation on a substantially vertical bearing stud 11. The bearing stud 60 depends from a bracket arm 12, which bracket arm is constructed from a substantially U-shaped strip of material providing parallel leads 13 joined at one end by a bight 14. The bight and the portions of the leads 65 13 adjacent thereto are cut away or rabbeted on the upper and lower edges at 15, and receive in the rabbeted portions upper and lower plates 16 and 17. The upper end of the bearing stud is reduced at 18 and provides a 70 shoulder 19 at its juncture with the lower portion, which shoulder abuts against the lower plate 17. The reduced portion extends through the alined openings in the plates 16 and 17 and is embraced by the bight 14. The 75 upper end of the reduced portion is threaded at 20, to receive a nut 21. The nut 21 overlies a cap 22 having a fluted periphery forming a plurality of grooves 23. A pair of rollers 24 are mounted for rotation on the angularly disposed terminals 25 of a pair of arms 26, the inner ends of which arms are provided with downturned extremities 27 fulcrumed in alined openings in the plates 16 and 17 and selectively engaged and embraced 80 in clamping relation by the retaining grooves 23 formed by the fluting. The nut 21 serves to retain the arms 26 adjusted and upon loosening of the nut it is obvious that the arms may be shifted selectively into the 85 grooves 23, whereby upon again tightening the nut the arms are held in adjusted position.

The leads 13 of the bracket arm 12 intermediate the ends, are riveted together by a rivet 28, which rivet is embraced by the bight 29 of a substantially V-shaped element 30. The upper arm 31 of the element 30 is provided with an angularly disposed terminal 32 and the lower arm 33 is provided with an 100 angularly disposed terminal 34, the terminal 32 being disposed in an upward direction and the terminal 34 in a downward direction, where they are selectively positioned in a series of bearing openings 35 and 36 formed in the upper and lower attaching members 37 and 38 which are secured to the supporting wall or member A. The free terminals of the leads 13 are provided with alined circular openings 39 in which a dog 40 is fulcrumed for swinging movement. The lower free end of the dog is adapted to selectively 105 110

engage with a line of rack teeth 41 formed on the arm 33 of the V-shaped element 30.

In use and operation of the device, the endless line B is trained around the grooved pulleys of a plurality of supporting devices, the bracket arms 12 being tilted or inclined with respect to the horizontal to produce, through the engagement of the rollers 24 with the leads of the line, a sufficient slack to preclude any possibility of displacement of the line from the grooved pulleys.

In some instances, the leads of the line where more than two supporting devices are employed, diverge from the pulley, as illustrated in Fig. 1, hence it is necessary to position the arms 26 thereof at an angle to each other, which angle will be varied according to the relative position of the other supporting devices used in connection therewith. In other instances where only a pair of supporting devices are employed and the leads of the line are disposed parallel, the arms 26 will be engaged in the respective grooves which will dispose said arms in parallel relation.

When the bracket arm 12 is inclined, the dog is engaged with the proper rack tooth 41 to hold the same at said inclined position. It is thus obvious that the pulleys arranged as heretofore set forth will permit of the free passage of the line with the clothes supported thereon, around the pulleys whereby every portion of the line may be used for the support of clothes. It is further obvious that an endless line supported in this manner will permit the user to remove from the line, any single piece of clothing or article without disturbing the remaining articles thereon. It is still further obvious that by providing and constructing an endless clothesline support in accordance with the invention, a maximum length of line is afforded in a minimum of space.

What is claimed is:

1. A supporting means for endless clothes lines, comprising a horizontal bracket having a head at its outer free end, a stud vertically depending from said head, a horizontally disposed pulley mounted on said stud for rota-

tion, a pair of horizontal arms overlying said head and pivoted thereto, said arms having laterally outturned terminals, rollers carried by said terminals for engaging over the clothesline leads at points beyond the periphery of the pulley, and means clampingly engaging over the roller supporting arms for retaining the same in relative diverging relation coinciding with the divergence of the line leads.

2. A supporting means for endless clotheslines, comprising a horizontal bracket having a head at its outer free end, a bearing stud depending vertically from the under side of the head, a horizontally disposed sheave mounted for rotation on said stud, a pair of horizontally disposed arms mounted over the upper side of the head and pivotally attached thereto, said arms having outturned angular terminals, rollers mounted on said terminals for engagement over the leads of the line at points beyond the periphery of the sheave, and a clamping cap having radial grooves selectively engageable with the roller supporting arms for retaining the same in relatively adjusted divergent relations to coincide with the divergence of the line leads.

3. A supporting means for endless clotheslines, comprising a horizontal bracket having a head at its outer free end, a bearing stud depending vertically from the under side of the head, a horizontally disposed sheave mounted for rotation on said stud, a pair of horizontally disposed arms mounted over the upper side of the head and pivotally attached thereto, said arms having outturned angular terminals, rollers mounted on said terminals for engagement over the leads of the line at points beyond the periphery of the sheave, a clamping cap having radial grooves selectively engageable with the roller supporting arms for retaining the same in relatively adjusted divergent relations to coincide with the divergence of the line leads, and means for detachably clamping the clamping cap in place to permit of adjustment of the roller supporting arms.

JOHN THOMAS PILKINGTON.
